CLOSURE FOR BOTTLES AND ANALOGOUS RECEPTACLES

William E. Smiley, Cazenovia, N. Y., assignor to
Paul H. Williams, Cazenovia, N. Y.

Application June 14, 1933, Serial No. 675,730

4 Claims. (Cl. 215—51)

This invention relates to a closure for bottles and analogous receptacles and refers more particularly to what is commonly known as a bottle cap having an opening therethrough and a normally closed foldable closure therefor adapted to be opened at will to form a pouring spout through which the contents of the receptacle may be discharged or withdrawn without removing the cap from the receptacle.

10 The caps for milk bottles and the like are preferably made in the form of flat circular disks of laminated or multi-ply paper-board suitably treated to render them impervious to air and moisture but capable of having portions of its layers easily 15 cut and separated to form the outlet opening and pouring spout therefor in the manner hereinafter described.

The main object, however, is to provide a cap of this character with an opening and a closure 20 therefor consisting of a tongue complementary to the opening and hinged at one end to the cap to be opened and closed at will, and opposite side wings also hinged to the cap to normally overlap upon the tongue and adapted to be unfolded by the opening of the tongue, together with 25 co-operative means on the tongue and wings respectively for holding the tongue in its open position against accidental closing and thereby to form the pouring spout.

30 One of the specific objects is to provide the outer face of the tongue with recesses complementary to the form of the wings to enable said wings to lie flatwise in the recesses when the tongue is closed so that both faces of the cap 35 including the tongue and wings will be flat and parallel for convenience in stacking and displacing the caps one by one from the stack during the operation of applying the caps to the bottles.

40 Another object is to provide portions of the marginal walls of the opening and corresponding portions of the marginal edges of the tongue with complementary rabbets engaging each other when the tongue is closed to limit the closing movement 45 of said tongue and at the same time to utilize portions of the flanges of the rabbets on the tongue as stops or abutments adapted to be engaged by the side wings when the tongue is opened to prevent accidental closing of the tongue.

50 Other objects and uses will be brought out in the following description.

In the drawing:—

Figure 1 is a top plan of a closure cap embodying the various features of my invention, the 55 tongue and wings being in their closed positions.

Figure 2 is an enlarged sectional view of the same taken on line 2—2, Figure 1.

Figure 3 is a top plan similar to Figure 1 except that the tongue and wings are in their open positions.

Figure 4 is an enlarged vertical sectional view taken on line 4—4, Figure 3.

Figures 5 and 6 are vertical sectional views taken respectively on lines 5—5 and 6—6, Figure 4, looking in opposite directions, the open wings 65 being shown by dotted lines in Figure 5 and by full lines in Figure 6.

Figures 7 and 8 are horizontal sectional views taken respectively on lines 7—7 and 8—8, Figure 6.

Figure 9 is an inverted plan view of the closure cap shown in Figure 1.

As illustrated, this closure cap comprises a flat circular disk 1 of laminated or multi-ply paper board paraffined or otherwise treated to render it impervious to air and moisture, the opposite faces of the disk cap and the several layers thereof being substantially parallel and firmly pressed together to form a unitary relatively rigid structure in which the layers are susceptible to division or splitting one from the other for a purpose hereinafter described.

This disk is provided with an opening 2 and a closure tongue 3 therefor and complementary thereto in form and size, said tongue being hinged at one end at 4 to the disk to permit it to be opened and closed at will.

A pair of similar opposite wings 5 are also hinged at 6 to the disk 1 at opposite sides of the opening 2 to swing laterally in opposite directions for engaging corresponding edges of the closure tongue 3 to hold the latter in its open position in a manner hereinafter explained.

As illustrated, the opening 2 is formed mainly in one half of the disk to extend radially from approximately the center of the disk to within a relatively short distance from the outer marginal edge of said disk and laterally equal distances from the center of said disk, said opening being preferably tapered from the center toward the periphery so that its inner end is relatively wider than its outer end.

The tongue 3 being complementary to the form and size of the opening 2 and hinged to the wider end wall of the opening, it is designed to effectively close the opening when in its folded or normal position, as shown in Figures 1, 2 and 9 and is adapted to be unfolded or opened to a position at substantially right angles to the plane of the disk, as shown in Figures 3 to 8 inclusive.

That is, the tongue 3 is hinged to the disk to swing to and from its closed position along the diametrical line indicated by dotted lines *a—a*, Figure 1, and has its opposite edges provided with laterally projecting flanges 7 a distance from the folding line somewhat less than the length of the wings 5 to form shoulders or abutments against which the outer ends of the wings 5 are adapted to engage when the tongue 3 and wings 5 are unfolded to its open position, as shown in Figure 4, for holding said tongue against accidental closing.

When the tongue 3 and wings 5 are opened to the positions shown in Figures 4 to 8 inclusive they constitute what may be termed a pouring spout for directing the liquid outwardly through the opening when the bottle or other receptacle with the cap thereon is wholly or partially inverted.

It is to be understood, however, that the same opening may be used for receiving a straw or siphon tube whereby the liquid may be withdrawn from the bottle while the latter is in a vertical position.

The wings 5 are preferably of similar triangular form with their wider ends hinged at 6 to the disk to swing to and from positions at substantially equal angles to the plane of said disk, the inner or rear edges of the wings being preferably disposed in a plane perpendicular to the plane of the disk when unfolded to the position shown in Figures 4 to 8 inclusive, said wings being approximately half the thickness of the tongue for a purpose presently described.

The outer face of the tongue 3 adjacent the disk 1 is provided with opposite recesses 8 each complementary to its corresponding wing 5 and of about the same depth as the wings so that when the wings and tongue are folded to their normal closed positions as shown in Figure 2, the wings will lie flatwise in their respective recesses 8.

In other words, the front edges as 9 of the folded wings 5 and the front walls as 10 of the recesses 8 are divergent outwardly from the center of the disk at equal angles so that when folded they will be in close engagement, while the outer faces of the folded wings will be disposed in substantially the same plane at the outer face of the folded tongue 3 as shown in Figures 1 and 2.

The rear edges as 11 of the wings 5 and corresponding rear walls as 11' of the recesses 8 of the tongue 3 are also slightly divergent forwardly from a point 12 a slight distance at the rear of the center folding line 2 and, therefore, a slight distance from the apex of the front walls 10 of the recess, as shown in Figure 1, so that the thickness of the intervening space between the apexes of the opposite walls of the recesses will be approximately half that of the disk to enable the tongue to fold and unfold more easily than would be the case if the thickness of the stock along the folding line were equal to that of the disk, said intervening space being indicated at 13, Figures 1, 2 and 3.

The width of the base along the folding line 6 of each of the wings 5 and adjacent side of the corresponding recess 8 is considerably less than that of the contiguous side wall of the opening 2, while the rear edge as 11 of each wing 5 and adjacent rear wall of the corresponding recess 8 is appreciably longer than the base width of the wing so that when the tongue and wings are unfolded to their open positions, the outer ends of the wings will engage the front faces of the

flanges 7 to hold the tongue in its open position against accidental closing.

Under these conditions, the rear edges of the wings 5 will abut against the adjacent edges of the open tongue 3 to hold them against accidental closing movement.

The tongue 3 and wings 5 are integral parts of the disk 1 in that the tongue 3 is integrally united at 4 to the rear wall of the opening 2 to fold and unfold to and from its closed position or from the position shown in Figures 1, 2 and 9 to the positions shown in Figures 3 to 8 inclusive.

The wings 5 are also integrally united at 6 to opposite walls of the opening 2 closely adjacent the folding line 4 of the tongue.

The portions of the walls of the opening 2 in front of the wings 5 are rabbeted at 14 from the top substantially half way through the thickness of the disk while the portions of the closed tongue 3 in front of the recesses 8 are similarly rabbeted at 15 from the underside through substantially half the thickness of the tongue and complementary to the rabbets 14 so that when the tongue is folded to its closed position, as shown in Figures 1, 2 and 9, the flanges of the rabbets 15 will enter the rabbets 14 with the result that the upper and lower faces of the tongue will be substantially coincident with the corresponding faces of the disk, as shown more clearly in Figure 2.

This engagement of the flanges of the tongue in the rabbets of the walls of the opening 2 serves to limit the closing movement of the tongue at which time the wings 5 may be folded into their respective recesses 8 in the upper face of the tongue to assist in holding the latter in its closed position with the assurance that the outer faces of the wings will lie in a plane substantially coincident with the corresponding faces of the disk.

If desired, the upper face of the disk at the front end or tip of the closed tongue 3 may be depressed at 16 to permit the insertion of a finger nail or other implement under the front edge of the tongue for opening the same.

The rabbets 14 and 15 in the disk 1 and tongue 3 respectively are preferably formed by cutting half way through the disk from the underside along the lines 17 and 17', Figure 9, and also by cutting half way through the disk from the upper side along the lines 18 and 18', Figure 1, in offset relation to the lines 17 and 17' and at the same time cutting half way through the disk from the upper side along the lines 9 or 10, 11 or 11', and 13, as shown in Figure 1, and then splitting or stripping the wings 5 and tongue 3 from the underlying portions of the disk.

It is, of course, understood that when the disk is cut through opposite faces in staggered relation to form the tongue 3 and when the cuts 9, 11 and 13 are properly made, the finger nail or other instrument may be inserted into the cut 13 to permit the wings 5 to be split from the underlying portions of the tongue and folded upwardly along the folding lines 6 whereupon the finger nail or other instrument may be inserted in the depression 16 and engaged with the adjacent end of the tongue to strip the latter from the disk along the lines of the rabbets 14 and 15 thereby unfolding the tongue along the folding line *a—a* and incidentally spreading the wings 5 until the rabbets 15 on opposite sides of the tongue are brought into registration with the rear edges of the wings, whereupon the latter automatically springs into the rabbets 15 for holding the tongue

in its open position against accidental closing and similarly holding the wings against accidental closing, as shown more clearly in Figure 7.

This method of cutting the disk along the lines 5 17 and 17' from the underside half way through the disk and simultaneously cutting the disk from the upper side half way through the thickness of the disk along the lines 18 and 18' and also along the lines 9, 11 and 13 to form the outer lines of the tongue 3 and wings 5, leaves the disk with both faces substantially flat and parallel so that they may be stacked one upon the other and then applied to the bottles one at a time by the usual mechanism commonly employed for 15 that purpose, thus providing a cap in which the opening therethrough is closed and hermetically sealed by the tongue 3 and wings 5 to prevent entrance of foreign matter into the receptacle and also preventing escape of liquid from the receptacle through the opening.

When it is desired to use the contents of the bottle without removing the cap, the wings and tongue may be unfolded to their open positions in the manner described and as shown in Figures 25 3 to 8 inclusive, whereupon the contents of the bottle may be discharged through the opening 2 and directed into another receptacle by means of the spout formed by the previously opened tongue and wings when the bottle is wholly or 30 partially inverted or as previously stated, the contents may be withdrawn through the opening by means of a suction tube or siphon while the bottle remains in an upright position.

In case a portion only of the liquid is discharged from the bottle, the wings 5 may be sprung outwardly by hand to enable the tongue 3 to be closed after which the wings will be folded flatwise into their corresponding recesses 3 in the tongue, thereby effectively closing the opening to prevent the entrance of foreign matter or escape of liquid from the receptacle.

What I claim is:

1. A closure for bottles and analogous receptacles comprising a fibrous member having a 45 tongue and opposite side wings cut therefrom to form an opening therethrough, said tongue and

wings being integrally united at one end to said member and normally closing said opening but adapted to unfold to form a pouring spout around one end and along opposite sides of the opening, said tongue having portions of its opposite sides rabbeted to receive the adjacent edges of the wings when the tongue and wings are unfolded to their open positions and thereby to hold the tongue in its open position against accidentally closing.

2. A bottle cap disk having an opening therethrough, a closure tongue for said opening integrally united at one end to said disk and adapted to be opened and closed at will, said tongue having recesses in one of its faces, and wings complementary to said recesses integrally united to said disk at opposite sides of the opening to fold into said recesses when the tongue is closed and to unfold when the tongue is opened to form a pouring spout, said tongue and wings having cooperative means for holding the tongue in its open position against accidental closing.

3. A bottle cap having an opening therethrough, a closure for said opening hinged to the disk to open and close and having portions of its opposite edges rabbeted, and wings hinged to the cap at opposite sides of the opening and adapted to fold over and upon the closure when the latter is closed and to unfold into engagement with the adjacent rabbeted portions when the closure is opened for holding said closure against accidental closing.

4. A bottle cap having an opening therethrough, a closure for said opening hinged to the disk to open and close and having portions of its opposite edges rabbeted, and wings hinged to the cap at opposite sides of the opening and adapted to fold over and upon the closure when the latter is closed and to unfold into engagement with the adjacent rabbeted portions when the closure is opened for holding said closure against accidental closing, said closure having recesses in its outer face complementary to the wings into which the latter are folded when the closure is closed.
